(57) **CLAIM**

The ornamental design for a toy assembly, as shown and described.

DESCRIPTION

FIG. 1 is a top, front and left perspective view of a toy assembly showing our new design;

FIG. 2 is a front elevation view thereof;

FIG. 3 is a rear elevation view thereof;

FIG. 4 is a left side elevational view thereof;

FIG. 5 is a right side elevational view thereof;

FIG. 6 is a top plan view thereof;

FIG. 7 is a top, front and left perspective view of one component of the toy assembly, shown separated from the other component for clarity and completeness of disclosure;

FIG. 8 is a front view of FIG. 7;

FIG. 9 is a rear view of FIG. 7;

FIG. 10 is a left side elevational view of FIG. 7;

FIG. 11 is a right side elevational view of FIG. 7;

FIG. 12 is a top plan view FIG. 7;

FIG. 13 is a top, front and left perspective view of the other component of the toy assembly, shown separated from the component shown in FIGS. 7-12 for clarity and completeness of disclosure;

FIG. 14 is a front view of FIG. 13;

FIG. 15 is a rear view of FIG. 13;

FIG. 16 is a left side elevational view of FIG. 13;

FIG. 17 is a right side elevational view of FIG. 13; and,

FIG. 18 is a top plan view of FIG. 13.

The broken lines are included for the purpose of illustrating portions of the toy assembly that form no part of the claimed design.

1 Claim, 18 Drawing Sheets
